PARK A. HEER, OF HILLSIDE, NEW JERSEY, ASSIGNOR TO THE SINGER MANUFACTURING COMPANY, OF ELIZABETH, NEW JERSEY, A CORPORATION OF NEW JERSEY

LUBRICATING SYSTEM FOR SEWING MACHINES

Application filed June 28, 1930. Serial No. 464,531.

This invention relates to a lubricating system for sewing machines and more particularly for high-speed power-driven machines which are especially constructed for stitching material treated with a sizing. Particles of this sizing not infrequently find their way into the sewing machine bearings, causing them to overheat and stick for want of proper lubricant, with a consequent interruption of the stitching operation.

It has for its object to provide a means of insuring a uniform delivery of lubricant to the more important sewing machine bearings whereby they are automatically or self-lubricated during the operation of the machine.

Another object of the invention is to provide a constant and uniform flow of lubricant to a bearing and to provide means for collecting and conducting the surplus lubricant away from such bearing.

A further object of the invention is to provide means for collecting and conducting the surplus lubricant from one bearing for lubricating an adjacent bearing.

The device comprises a lubricant receptacle or reservoir mounted upon the overhanging sewing machine bracket-arm. Depending from the reservoir, and terminating above the inside bottom of the latter, are a series of lubricant conduits entering enlarged sleeves formed upon the upper ends of lubricant-delivery tubes which tubes lead, respectively, to the front, middle and rear main shaft-bearings. Lubricant is supplied to the reservoir and automatically fed into the delivery tubes by capillary attraction by means of lamp-wicks extending from the bottom of the reservoir over and into the ends of the conduits.

The lubricant-delivery tubes lead to and terminate above bearing-bushings provided with absorbent packing chambers disposed longitudinally of the shaft. These chambers are filled preferably with felt or cotton waste packing which, being in contact with the shaft, feeds lubricant thereto supplied through the delivery tubes from the reservoir.

The surplus lubricant emerging from both ends of the bearing is collected and con-

ducted away from the bearing. This is accomplished by forming a lubricant-collecting flange in one end of the bearing-bushing shaft-aperture and providing a lubricant throwing flange within the lubricant-collecting flange upon an adjacent revolving part, such as the sewing machine driving pulley, crank-arm or eccentric. Surplus lubricant emerging at that end of the bearing is thrown by centrifugal force into the circular cavity formed by the lubricant-collecting flange and gradually finds its way to the lowest portion of such cavity from which it is led to the other end of the bearing by an overflow duct or aperture in the bushing provided for the purpose.

The other end of the bearing-bushing is formed with a reduced portion which is surrounded by the overhanging flange of a lubricant collector-ring loosely carried by the shaft but rotatable therewith. The overflow duct or aperture from the first-named end of the bearing terminates in the cavity formed between the reduced end of the bushing and the collector ring.

Surplus lubricant emerging from both ends of the bearing gradually finds its way into the circular cavity formed in the collector ring from which it is ejected through a laterally projecting tube. This lubricant may either be collected or utilized to lubricate an adjacent rotary bearing such as is formed by the connection of a pitman with a crank-arm of the shaft.

In the accompanying drawings Fig. 1 is a rear side elevation of the device applied to a well-known form of Singer sewing machine, a portion of the frame being shown in section. Fig. 2 is a top plan view of the sewing machine bed with the upright standard in section. Fig. 3 is an enlarged detail sectional view of a portion of the main-shaft bearing lug 4 with adjacent movable bearings lubricated from the main-shaft bearing. Fig. 4 is a similar enlarged detail view of a portion of the main-shaft bearing lug 5. Fig. 5 is a detail view, partly in section, of the bearing bushing 40 with its adjacent lubricant collecting ring and eccentric.

tric. Fig. 6 are detail views of the bearing block 46 within the forked arm 50.

As herein represented, the device is applied to a sewing machine comprising the usual bed 1 from which rises the standard 2 which carries an overhanging arm 3. Journaled in bearing lugs 4, 5 and 6, rising from the bed 1, is the main-shaft 7 formed with the crank 8 embraced by the pitman 9 for actuating the needle-bar mechanism (not shown) housed in the overhanging arm 3.

Secured to the overhanging arm 3, at its junction with the upright standard 2, is a lubricant receptacle or reservoir 10. Depending from the reservoir, and extending above the bottom of the latter, are a series of enlarged sleeves 11, 12, 13 and 14 terminating in lubricant conduits 15, 16, 17 and 18 which deliver lubricant to the bearings. Lamp-wicks 19, extending from the bottom of the reservoir over and into the enlarged sleeves, cause the flow of lubricant into the conduits by capillary attraction.

The conduit 15 supplies lubricant to the main-shaft bearing formed in the lug 6 and the adjacent movable bearing on the crank 8 of the main-shaft 7. The lug 6 is recessed to receive a stationary bearing member or bushing 20 provided with an aperture 21 in which the shaft 7 rotates. The upper portion of the bearing-bushing is formed with a chamber or well 22, which is filled with a soft oil-absorbent packing such as felt or waste which is saturated with lubricant from the reservoir 10 fed to it through the conduit 15. The conduit 15 enters an inclined aperture 15' in the sewing machine standard 2 which delivers the lubricant intermediate the bearing ends in order to insure its even distribution in the bearing. The chamber or well 22 is disposed longitudinally of the main-shaft 7 and the bottom of the chamber is provided with a slot 23 extending into the shaft aperture 21 of the bushing through which lubricant is supplied to the shaft 7.

The end of the bearing-bushing 20, adjacent the driving pulley 24, is undercut at 25 to form a lubricant-collecting flange, while the hub of the adjacent driving pulley is formed with a projecting lubricant-throwing flange 26 disposed within the undercut lubricant-collecting flange 25 of the bearing-bushing 20. The driving pulley being secured to the main-shaft 7 by the set screws 27, and with its hub formed with the lubricant-throwing flange 26, rotates with the shaft 7.

During the rotation of the shaft 7, lubricant which finds its way out of the pulley-end of the bearing, is caught by the face of the lubricant-throwing flange 26 from the periphery of which it is thrown by centrifugal force into the adjacent circular chamber or cavity formed by the lubricant-col-

lecting flange 25 from which it gradually finds its way into the lowest portion of such cavity whence it is led away by the overflow duct or passage 28 formed in and extending lengthwise of the bearing-bushing 20. 70

The other end of the bearing-bushing 20, i. e., the end adjacent the crank 8 of the main-shaft 7, is surrounded by the lubricant-collecting ring 29 which is loose upon but rotates with the shaft. The collecting ring 29 has an overhanging ledge or in-turned lip 30 forming with the end of the bearing-bushing 20 a continuous lubricant-collecting cavity 31 concentric therewith throughout its periphery. 80

During the operation of the machine, lubricant which finds its way out of the end of the bearing adjacent the crank 8 enters the lubricant-collecting chamber or cavity 31 of the collecting ring 29 where it is joined by the spent lubricant from the pulley end of the bearing passing through the overflow duct or passage 28. 85

A cap-screw 7', entering the end of the main-shaft 7, seals the shaft opening in the driving pulley 24 and prevents escape of spent lubricant at that point. 90

The lubricant-collecting ring 29 is provided with a laterally projecting tube 32 whose aperture is flush with the inner wall of the collecting ring. As previously stated, the collecting ring 29 is loose upon the main-shaft 7 but its rotation with the latter is insured by the tube 32 entering a suitable aperture 33 in the crank 8 through which 95 and its extension aperture 34 in the crank-pin 35, lubricant is passed to the bearing embraced by the pitman 9. Surplus lubricant emerges from the aperture 36 in the crank 8. 100

From the foregoing it will be observed that surplus lubricant emerging from either end of the stationary bearing 21 is collected and conducted to the adjacent movable crank bearing 35 of the main-shaft 7. 110

The conduit 16 supplies lubricant to the main-shaft bearing in the lug 5 and the looper actuating fork adjacent one side thereof. The delivery end of this conduit terminates at the aperture 37 in the lug 5 through which lubricant reaches the absorbent packing 38 in the chamber or well 39 formed in the stationary bearing member or bushing 40, see Figs. 4 and 5. The bushing is provided with a reduced portion 41 which enters a counter-bore 42 in the adjacent eccentric 43 secured to the main-shaft 7 by the set screw 44. Adjoining the bushing 40, the eccentric 43 is provided with the inclined aperture 45 through which lubricant overflowing from that end of the bearing-bushing 40 is ejected to lubricate the bearing of the block 46 embracing the eccentric 43. The bearing-block 46 is provided with the lateral aperture 47 and external groove 48 130

through which lubricant emerging from the bearing of the block 46 upon the eccentric 43 is passed to the lower bearing-seat 49 of the forked arm 50 embracing the block 46.

- 5 The upper wall of the block 46 is provided with an aperture 47' through which lubricant emerging from the bearing of the block upon the eccentric 43 is delivered to the upper bearing-seat 49' of the forked arm 50,
- 10 The forked arm 50 is secured by the set screw 51 upon one end of the longitudinal shaft 52 journaled in the bed 7 and upon the other end of the shaft 52 is clamped the looper support 53 provided with the looper 54. The eccentric 43 with the connections just described impart to the looper its sidewise or needle-avoiding movements.

The conduit 17 supplies lubricant to the looper-actuating mechanism adjacent the other end of the main-shaft bearing-lug 5 through the medium of the bushing 40. For this purpose, the conduit 17 enters an inclined aperture 55 in the lug 5 which aperture registers with a similar aperture 56 in the bushing 40 communicating with the angularly disposed groove 57 upon the inner bearing-wall of the bushing 40. The reduced portion 58 of the bushing 40 extending beyond the lug 5 is surrounded by the lubricant-collecting ring 59 whose inner face 60 bears snugly against the bushing 40. The reduced end 58 of the bushing is spaced from the inner face of the collecting ring 59, forming with the latter, a lubricant-collecting cavity 61. Extending laterally from the collecting-ring 59 is a tube 62 which registers with an aperture 63 in the crank-arm 64 of the main-shaft 7. Lubricant from the conduit 17 enters the shaft-bearing through the apertures 55 and 56 and, due to the angularly disposed slot 57 in the inner wall of the bushing 40, the lubricant is directed into the collecting-cavity 61 from which it is ejected by centrifugal force through the tube 62 into the aperture 63 from which it reaches the crank-bearing through the slot 65. Surplus lubricant is passed out through the aperture 66 in the crank-arm 64.

The bearing upon the crank-arm 64 is 50 embraced by the strap-end of a pitman 67 whose lower end is pivotally connected by a ball-stud 68 with one arm 69 of a two-armed rocker 70 journaled in the bed 1 of the machine. The other arm 71 of the rocker 55 has a link-connection 72 with the looper-support 53. The mechanism just described imparts loop-seizing and -shedding movements to the looper 54.

The conduit 18 supplies lubricant to the 60 main-shaft bearing in the lug 4 and the feed-dog actuating mechanism adjacent thereto. This conduit terminates at the upper end of an aperture 73 in the lug 4 which is also provided with a stationary bearing-member 65 or bushing 74 having the chamber or well

75 filled with a soft oil-absorbent packing such as felt or waste which becomes saturated with lubricant supplied to it from the reservoir 10 and through a longitudinal slit 75' in the wall of the bushing reaches the shaft 7. 170

The bushing 74 extends at both ends beyond the bearing-lug 4, both ends being reduced and undercut to form the lubricant drip-edges 76. Secured to the main-shaft 7 by the fastening screw 77 is the collar 78 of the feed-lift eccentric 79. The collar 78 is counter-bored at one end to form, with the drip-edge 76 of the bushing 74, a lubricant-collecting cavity 80 which communicates with an aperture 81 extending lengthwise of the eccentric and parallel with the main-shaft 7. Surplus lubricant emerging at this end of the bearing-bushing 74 finds its way into the lubricant-collecting cavity 80 whence, by centrifugal force, it enters the aperture 81 through which a portion finds its way through the aperture 82 in the eccentric 79 to lubricate the bearing of the feed-lift pitman 83 embracing the eccentric. Surplus lubricant is ejected from the open end of the aperture 81. The feed-lift pitman 83 is pivotally connected by the pin 84 with the feed-bar 85 whose other end is supported upon the rocker 86 journaled upon the shaft 87 in a well known manner. 180

The other reduced end of the bearing-bushing 74 in the lug 4 is surrounded by the counter-bored end of the feed-actuating eccentric 88 secured to the main-shaft 7 by the screws 89. The oil-collecting cavity 90 at this end of the bushing communicates with the inclined aperture 91 extending to the outer wall of the feed-actuating eccentric 88 through which surplus lubricant emerging from this end of the main-shaft bearing in the lug 4 reaches the bearing of the feed-actuating pitman 92 embracing the eccentric 88. 190

It will be noted from the foregoing description that I have provided an arrangement which supplies an uninterrupted flow of lubricant from a reservoir to the principal bearings of a sewing machine, permitting the latter to be operated at a comparatively high rate of speed under adverse conditions. 200

It will be obvious that this lubricating arrangement is equally applicable to machines other than sewing machines for operation at high speed. 115

Having thus set forth the nature of the invention, what I claim herein is:—

1. A lubricating device for bearings having an overflow duct, in combination with a shaft, a lubricant throwing flange at one end of said bearing and rotatable with said shaft, a stationary lubricant-collecting flange surrounding said throwing flange, said flanges forming between them an oil 125

collecting cavity communicating with said overflow duct, a lubricant-collecting ring rotatable with said shaft at the other end of said bearing and also communicating with said overflow duct, and means for conducting surplus lubricant away from said collecting ring.

2. In combination, a stationary bearing member, a shaft journaled therein and having a crank-bearing adjacent one end of said bearing-member, a rotary lubricant-collecting ring fixed to said shaft and surrounding said end of said bearing-member, a lubricant-duct leading from said lubricant-collecting ring to said crank-bearing, a lubricant-throwing flange at the other end of said bearing-member and rotatable with said shaft, a stationary lubricant-collecting flange surrounding said last-named lubricant-throwing flange, and a lubricant-duct leading from said last-named stationary lubricant-collecting flange lengthwise of the stationary bearing-member and discharging into said first-named rotary lubricant-collecting ring.

3. A lubricating device for bearings, comprising a stationary bearing bushing having an overflow duct, an undercut lubricant collecting flange formed in one end of said bearing bushing, a shaft, a lubricant-throwing flange rotatable with said shaft and surrounded by the undercut lubricant-collecting flange, said flanges forming between them a lubricant collecting cavity communicating with said overflow duct.

In testimony whereof I have signed my name to this specification.

PARK A. HERR.
